STEWART E. SEAMAN, OF BROOKLYN, NEW YORK, ASSIGNOR TO SEAMAN WASTE WOOD CHEMICAL COMPANY INC., OF NEW YORK, N. Y., A CORPORATION OF NEW YORK.

ART OF DESTRUCTIVE DISTILLATION.

1,236,884.

Specification of Letters Patent. Patented Aug. 14, 1917.

Application filed May 27, 1916. Serial No. 100,190.

To all whom it may concern:

Be it known that I, STEWART E. SEAMAN, a citizen of the United States, and a resident of the borough of Brooklyn, county of 5 Kings, and State of New York, have invented a new and useful Improvement in the Art of Destructive Distillation, of which the following is a full, clear, and exact description.

10 My invention relates to improvements in the art of destructive distillation of wood, hull bran, nut shells, cotton-seed hulls, cellulose, lignum, and other materials containing distillates worth recovering, and preferably such as also contain matter which can be converted into a commercial charcoal. The object of my invention is to provide a method of distillation, preferably continuous, in which the charge is constantly fed 15 to a retort, the vapors and gases continuously withdrawn, and the carbonized or residue material also discharged. More particularly my invention is intended to provide means whereby the charge is compressed as it enters the heated retort thus forming a seal which prevents the escape of gases and vapors through the intake, and also excluding by compression the oxygen in the charge. Both these features are important because the escape of gases through 20 the inlet is likely to prove disastrous, besides wasting the gases, and if oxygen in any great quantity enters the retort it produces combustion and sometimes explosions.

25 Another object of my invention is to arrange the discharge of the carbonized or other residue material so that it will not interfere with the free drawing-off of gases and vapor but will also serve as a seal to prevent the escape of such gases and vapor through the outlet for residue matter. In general, my invention is intended to provide a simple, efficient and thoroughly commercial method by which a rotary retort can be used so that the charge is kept agitated and the heat evenly applied to it, to provide means for having the charge seal the inlet, the discharge of the residue material seal the outlet, and thus provide for a continuous 30 withdrawal of gases and consequent continuous distillation.

Reference is to be had to the accompanying drawings forming a part of this specification, in which similar reference charac-

ters indicate corresponding parts in all the views.

The figure is a longitudinal section of an apparatus suitable for carrying my invention into effect.

As illustrated a rotary retort 10, preferably cylindrical, is horizontally supported in masonry 11. The retort can be heated in any suitable way, and I have shown a fire box 12 connected with a distributing chamber 13 having flues 14 through which the hot products of combustion pass to a heating chamber 15 directly beneath the retort, and from thence the products of combustion pass out through a stack 16. The retort 10 has its inlet end reduced forming a neck 17 which is mounted in suitable bearings 18, while the lower end of the retort passes through a gland 19 and enters a hollow head 20.

The retort can be rotated in any suitable way and as shown the neck 17 serves the purpose of a shaft and is provided with a worm wheel 21 driven by a worm 22. A thrust collar 23 is placed on the neck next the worm wheel to provide against too much end movement of the retort. At its outer end the neck 17 is provided with a gland 24 which receives the feed pipe 25, this serving as an extension of the neck 17, and it is shown supported by a suitable bracket 26. A hopper 27 delivers into the feed pipe and the material to be treated passes from the hopper into the feed pipe.

The feed pipe 24 extends outward beyond the hopper, and in it is a plunger 28 which reciprocates below the mouth of the hopper and rams the charge into the feed pipe and neck 17. The charge thus becomes very much compressed so that the gases and vapors of the retort cannot pass back through it, and the stroke of the plunger brings it at its inner movement slightly short of the inner wall of the mouth of the hopper as shown at 27^a so that the oxygen in the charge is forced outward by compression, and clearance is provided so that it can pass up through the loose charge in the hopper.

The plunger 28 can be moved in any convenient manner and I have shown it connected by a rod 29 with an eccentric 30 working in the casing 31 at the outer end of the pipe 25 and driven by a pulley 32. This affords a convenient and efficient means of

ramming the charge into the pipe and inlet end of the retort, thus sealing it and excluding the oxygen, but obviously other means for compressing the charge at this point and 5 expelling the oxygen thereby can be used without in the least affecting the invention.

The retort at its lower or discharge end is preferably supported on a spider 33 which is carried by a shaft 34, and the latter 10 extends outward through a gland in the head 20 and is mounted in a bearing 35 on the bracket 36 which is secured to the head 20. From the upper part of the head 20 the vapors and gases are carried by a pipe 15 37 and delivered into a suitable condenser 38. Obviously the gases can be taken out from other parts of the retort, but I find that this arrangement works satisfactorily.

At its lower side the head 20 forms a 20 pocket 39, and in this is arranged a screw conveyer 40 which extends transversely of the retort through a suitable pipe, and discharges into a hopper 41 which in turn delivers into a pipe 42, this being provided 25 with a plunger 43 which rams the carbonized material in the pipe 42 and expels it into a suitable receptacle 44. Thus the carbonized material as it is withdrawn is also compressed and makes an effective seal 30 which prevents the escape of gases through the outlet for the charcoal or carbonized material, and while I have tried this arrangement and it works satisfactorily, I do not limit the invention to this means of 35 compressing the carbonized material to form a seal.

It will thus be seen that I provide a continuous means for supplying a charge to the retort, for withdrawing the gases and 40 vapors liberated by the heat in the retort, and also provide a convenient means for discharging the carbonized material and make this material a seal against the escape of said gases and vapors. It will be seen 45 therefore that oxygen is excluded from the retort, that a continuous flow of material into and through it is provided, a continuous outflow of vapors and gases, and that the means as a whole is simple and effective.

50 While I have shown my improvement as applied to the destructive distillation of finely divided cellulose material, it will be understood that in some of its broader aspects it is not limited to the destructive 55 distillation, in which case the residue products after the vapors and gases are withdrawn from the retort may not be carbonized, and while my invention is best carried out in a continuous process, it will be seen 60 that if the process is not continuous still it may involve many features of my invention.

I claim:—

1. The improvement in the art of distilling wood or other similar materials which 65 consists in distilling such material in a re-

tort and compressing such material as it is fed to the retort to expel the air therefrom.

2. The improvement in the art of distilling wood or other similar material which consists in distilling such material in a retort, 70 compressing such material while in a finely divided form to expel the air therefrom, and in forcing such material while thus compressed into the retort.

3. The improvement in the art of distilling 75 wood or other similar material, which consists in compressing the said material, feeding such compressed material to a retort, and converting such compressed material into a seal during the feeding and distilling 80 operations to prevent the escape of gases and vapors from the retort through the feed inlet.

4. The improvement in the art of distilling wood or other similar material, which consists in compressing the said material while in a finely divided state, feeding such compressed material to the retort, and converting such compressed material into a seal during the feeding and distilling 85 operations to prevent the escape of gases and vapors from the retort through the feed inlet.

5. The improvement in the art of distilling wood or other similar material, which consists in forcing such material while in a 95 finely divided state into an inlet passageway leading to the retort, compressing it therein to cause it to fill the same tightly and forcing the said compressed and tightly fitting material through the said passageway and into the retort during the distilling 100 operation, whereby the escape of gases from the retort through the inlet passageway will be prevented during the feeding operation.

6. The improvement in the art of distilling 105 wood or other similar material, which consists in forcing such material into an inlet passageway leading to the retort, compressing it therein to cause it to fill the same tightly and forcing the said compressed and 110 tightly fitting material through the said passageway and into the retort during the distilling operation, whereby the escape of gases from the retort through the inlet passageway will be prevented during the feeding 115 operation.

7. The improvement in the art of destructive distillation of wood or other similar material, which consists in heating the material in a retort and utilizing the carbonized material as it is withdrawn from the retort to effect a continuous and positive seal in the outlet of the retort against the escape of gaseous products through said outlet. 120

8. The improvement in the art of continuous distillation of wood or other similar material, which consists in heating the material in a retort, drawing off the gases and vapors from the retort, and utilizing the 130

residue material as it is withdrawn from the retort to continuously and positively seal the outlet for such material against the escape of gaseous products from the retort 5 through said outlet.

9. The improvement in the art of continuous distillation of wood or other similar material, which consists in forcing the residue material resulting from the distillation into the 10 discharge passageway, compressing it tightly therein and forcing it through such discharge passageway in the said tightly compressed condition, whereby the material will be discharged from the retort without permitting the escape of gases from the retort 15 through the discharge passageway.

10. The improvement in the art of distillation of wood or other similar material, which consists in freeing said material from 20 its gases and vapors in a heated retort, drawing off the said gaseous products, forcing the carbonized material resulting from the distillation into a discharge passageway, compressing it tightly therein, constantly 25 maintaining it in such compressed state and forcing it from such discharge passageway in said tightly compressed condition, whereby the material will be discharged from the retort without permitting the escape of gases 30 from the retort through the discharge passageway.

11. The herein described improvement in the art of destructive distillation of wood and other similar materials, which consists 35 in treating the charge in a sealed retort, compressing the charge at the inlet end of the retort so as to seal the latter against the escape of gases and expel oxygen from the charge, utilizing the discharge of carbonized material from the retort to effect a seal, and withdrawing and condensing the gases 40 and vapors from the retort.

12. The herein described improvement in the art of destructive distillation of wood 45 and other similar material, which consists in distilling the charge in a sealed retort and compressing the charge before it enters the retort, thereby expelling the oxygen from the charge and converting the compressed 50 charge into a seal against the escape of gases and vapors from the retort.

13. The herein described improvement in the art of destructive distillation of wood and other similar material, which consists in 55 heating the charge in a suitable retort, drawing off the gaseous products from the retort, condensing said gaseous products, compressing the charge before it enters the retort so as to seal the latter against escape of gases 60 from the inlet end, withdrawing the carbonized products from the retort, and compressing the carbonized products as they leave the retort so as to effect a seal against the escape of gases.

14. The herein described improvement in

the art of destructive distillation of wood and other similar material, which consists in continuously feeding material to the retort, compressing the material before it enters the retort so as to make it serve as a 70 seal and so as to expel the oxygen therefrom, withdrawing the gaseous products of the material from the retort, discharging the carbonized products from the retort, and compressing the carbonized products 75 as they are withdrawn thereby sealing the retort at the discharge end.

15. The herein described improvement in the art of continuous destructive distillation of wood and other similar material, 80 which consists in continuously feeding the material to be treated to the retort through a feed pipe, compressing the charge in the feed pipe during the distilling operation so as to seal the retort and expel oxygen from 85 the charge, and maintaining the material in a compressed condition in the said feed pipe so as to effect a continuous and positive seal.

16. The herein described improvement in the art of destructive distillation of wood 90 and other similar material which consists in distilling the material in a closed retort, feeding the material to be treated through a feed pipe to the retort, and ramming the material in said pipe thus forming it into a 95 seal and at the same time expelling oxygen therefrom.

17. The herein described improvement in the art of destructive distillation of wood and other similar material, which consists 100 in continuously feeding the charge to the retort, compressing the material as it is fed thus forming a seal and eliminating oxygen from the charge, applying heat to the retort, continuously withdrawing carbonized material from the retort, compressing said carbonized material to form a seal, and withdrawing and condensing the gaseous products from the retort.

18. The herein described improvement in 110 the art of destructive distillation of wood and other similar material, which consists in heating the material in a retort, utilizing the charge before it enters the retort to seal the inlet end of the latter against the escape 115 of gaseous products from the retort, utilizing the carbonized material as it is withdrawn from the retort to seal the outlet against the escape of such gaseous products, and withdrawing the gaseous products. 120

19. The herein described improvement in the art of continuous destructive distillation of wood and other similar materials, which consists in continuously feeding a charge to and withdrawing the carbonized 125 material from a retort, utilizing the charge as it enters the retort to seal the latter against the escape of gaseous products, utilizing the carbonized material as it is withdrawn to seal the outlet against the escape 130

of gaseous products, and withdrawing said gaseous products through a separate vent.

20. The improvement in the art of distillation of wood or other similar material, which consists in heating the material in a retort, and utilizing the material as it is fed into the retort to seal the inlet against the

escape of gaseous products from the retort through said inlet.
